UNITED STATES PATENT OFFICE.

THEODORE E. WIEDERSHEIM, JR., OF PHILADELPHIA, PENNSYLVANIA.

DESIGN FOR PAPER BOX.

SPECIFICATION forming part of Design No. 25,195, dated February 25, 1896.

Application filed November 18, 1895. Serial No. 569,877. Term of patent 34 years.

To all whom it may concern:

Be it known that I, THEODORE E. WIEDERSHEIM, Jr., a citizen of the United States, residing in the city and county of Philadelphia, State of Pennsylvania, have invented and produced a new and original Design for Paper and other Boxes, of which the following is a specification, reference being had to the accompanying drawings, forming part thereof.

The leading feature of my design for a box is a body simulating a cage and a partition therein back of the grating thereof, having thereon a representation simulating an animal, the same being independent of said grating, leaving a storage-chamber rearward of said partition without disturbing the independence of the grating and animal-appearing partition.

Figure 1 represents a perspective view of a

box embodying my design. Fig. 2 represents a vertical section thereof in line X X, Fig. 1.

Similar letters of reference indicate corresponding parts in the two figures.

In the drawings, A designates the body of a paper box, and B the lid thereof. On one of the sides of the box is the grating C, the same simulating a cage.

Within the box back of the grating is the flap D, on which is a representation simulating an animal, constituting a partition independent of said grating, leaving a chamber rearward of said partition.

What I claim is—

The design for a box, substantially as described and shown.

THEODORE E. WIEDERSHEIM, Jr.
